UNITED STATES PATENT OFFICE.

STEPHEN D. BAKER, OF NEW YORK, N. Y.

DESIGN FOR A WALL-POST.

54,574.

Specification for Design.

Patented Mar. 9, 1920.

Application filed July 7, 1917. Serial No. 179,281. Term of patent 14 years.

To all whom it may concern:

Be it known that I, STEPHEN D. BAKER, a citizen of the United States, residing at New York city, in the county of New York and State of New York, have invented a new, original, and ornamental Design for a Wall-Post, of which the following is a specification, reference being had to the accompanying drawing, forming a part hereof.

The figure is a perspective view of the wall post, taken from a point to the right and forward of the same, illustrating my new design.

I claim:

The ornamental design for a wall post, substantially as shown.

In testimony whereof, I affix my signature.

STEPHEN D. BAKER.
